Primary Examiner — Susan Moon Lee(74) *Attorney, Agent, or Firm* — Kunzler Bean & Adamson, PC; Michael Bartholomew(57) **CLAIM**

The ornamental design for a bird feeder, as shown and described.

DESCRIPTION

FIG. 1 is a front, left and top perspective view of a bird feeder, showing our design.

FIG. 2 is a rear, right and bottom perspective view thereof.

FIG. 3 is a front, left and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 1; and, FIG. 11 is an enlarged view of detail 11 in FIG. 1.

The broken lines depict portions of the bird feeder that form no part of the claimed design. The dot-dash broken lines in FIGS. 1, 10, and 11 depict the boundaries of the enlargements that form no part of the claimed design.

1 Claim, 11 Drawing Sheets(56)
